UNITED STATES PATENT OFFICE

2,596,283

MOUNTING FOR LIQUID CONTAINERS

Edward M. O'Neill, San Francisco, Calif., assignor
to Union Machine Company, San Francisco,
Calif., a corporation of California

Application May 20, 1946, Serial No. 670,910

9 Claims. (Cl. 248—315)

1

This invention relates to apparatus for making mixtures, such for example as for mixing paints, lacquers, enamels or the like or their ingredients to secure a predetermined tint. More particularly, it relates to an arrangement for supporting the individual cans containing such ingredients.

This application is a continuation in part of an application filed in the name of Edward M. O'Neill on August 24, 1942, entitled "Mixing Apparatus" and bearing Serial No. 455,833, now Patent No. 2,438,574, issued March 30, 1948. An apparatus of this same general type is disclosed in Patent No. 2,333,951 granted to Edward M. O'Neill on November 9, 1943, and also entitled "Mixing Apparatus."

In such apparatus, a revolvable table is provided with the individual paint cans detachably secured thereto adjacent its periphery, angular movement of the table serving to position successively, the chosen cans in position to discharge into the container for the mixture. Each can is provided with valve controlled outlet and additionally with a rotatable agitator for stirring the contents before discharge to form the mixture. The agitators are each carried by a vertical shaft depending into the can, and are arranged to be driven simultaneously by a common motor.

It is an object of this invention to provide improved means for mounting such cans on the table; which serves to firmly secure the can to the table; and which is easily operable to permit the removal and replacement of the cans.

It is another object of this invention to provide an improved form of agitator which facilitates removal and replacement of the can.

It is another object of this invention to provide an improved seal about the agitator shaft where it enters the container.

It is still another object of this invention to provide an improved closure for an atmospheric vent in the can.

This invention possesses many other advantages, and has other objects which may be made more clearly apparent from a consideration of one embodiment of the invention. For this purpose there is shown a form in the drawings accompanying and forming part of the present specification. The form will now be described in detail illustrating the general principles of the invention; but it is to be understood that this detailed description is not to be taken in a limiting sense, since the scope of this invention is best defined by the appended claims.

In the drawing:

2 Figure 1 is an elevation partly in section, showing the improved container mount and agitator arrangement;

5 Fig. 2 is a section taken as indicated by line 2—2 of Fig. 1;

Fig. 3 is a detail section, taken as indicated by line 3—3 of Fig. 2;

10 Figs. 4 and 5 are fragmentary sections taken as indicated by correspondingly numbered lines 10 on Fig. 1; and

Figs. 6 and 7 are sections in an enlarged scale taken as indicated by correspondingly numbered lines on Fig. 5.

15 Referring to the drawing, particularly Fig. 1, the can or container 2 may be a conventional paint can. However, it is provided with a special cover 3, as will be discussed later, and with a valve controlled outlet, such as disclosed in the above mentioned patent. The can 2 is suspended

20 below the supporting member or table 4 by a hanger or bracket 5 secured to the table, and which is optionally operable to release the can, to allow insertion and removal thereof.

25 For this purpose the bracket 5 has a band 6 adapted to embrace the can 2 tightly adjacent the upper end thereof. An upper lip 2-a on the can 2 ensures against the can slipping downwardly within the band 6. The ends of the band 6 are provided respectively with ears 7 and 8 carrying clamping means 9 for tightening the band about the can 2. When the clamping means are loosened, the natural resilience of the band 6 causes it to spring open to free the can, whereby the can may be removed by lowering it in an axial direction.

30 The clamp 9 comprises a rod or bar 10 slidably mounted in suitable apertures in the ears 7 and 8, and having a head 11 engaging one of the ears, as ear 7. A cam member 12 is pivotally mounted at 13 on the rod 10, and has an eccentric surface 14 engaging the other ear 8, as well as an elongated operating handle 15. From an inspection of Fig. 1, it will be apparent that rotation of the cam member 12 in a clockwise direction from the position shown will bring portions of the eccentric surface 14 of progressively decreasing radius against ear 8, allowing ears 7 and 8 to move apart and the band 6 to open. A return movement of member 12 to the position shown 35 serves to clamp the band 6 about the can 2, such movement being limited by engagement with the ear 8 of the flat portion 14-a of the cam surface 14 formed where the cam surface merges with the surface 16 of the handle 15. The cam 40

45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

3

between the surface 14 and ear 8 that the tendency of the band 6 to spring open is incapable of causing the member 12 to rotate.

The band 6 is suspended beneath the table 4 by a plurality of arms as 17, 18 and 19 with ears 20, 21 and 22 respectively, through which pass bolts 23, 24 and 25 securing the arms to the table 4. To facilitate the clamping of the band 6 about a can 2 and its release thereof, two of the arms preferably those adjacent the clamp 9 are arranged to move with the band 6. Thus, arm 18 is fixed to the table 4 by bolt 24, while arms 17 and 19 are permitted limited transverse movement with respect to the table.

Thus, referring to Figs. 2 and 3, it will be seen that the bolt 25 does not clamp the ear 22 against the member 4, but merely supports the ear 22 by a washer 26 on the bolt head 25-a. A separator 27 is interposed between the washer 26 and member 4 to provide clearance for the ear 22. This ear 22 has a large opening 28 accommodating the separator 27 and providing sufficient clearance about the separator to allow the required movement of the arm 19. A similar arrangement is provided for supporting the other movable arm 17.

As pointed out in said patent, it is desirable to stir or agitate the contents of the can 2 before use. For this purpose an agitator 30 is provided in the can 2, supported near the bottom of the can by means of a rotatable spindle 31. The agitator 30 may be formed conveniently of a flat metal bar having an intermediate portion 30-a of reduced width secured as by brazing in a slot in the lower end of the spindle 31. Those portions of the bar 30 on opposite sides of the spindle are bent so that the broad surfaces of the bar lie in planes oblique to the spindle axis. The spindle 31 is detachably connected by a coupling 32 to be driven and guided by a vertical shaft 33, rotatably mounted in a bearing 34 supported on the table member 4. A pulley 35 is fixed on the upper end of the shaft 33 and is connected with a source of power (not shown) by means of a belt 36.

Since the spindle 31 must pass through the cover of the container 2, it is preferred to provide a special cover 3 which is arranged for this purpose and substituted for the original cover before can 2 is inserted in the bracket 5. The cover 3 is substantially identical with the cover usually employed on cans such as 2, except for the provision of the means 39 for supporting the spindle 31 and providing a seal around it.

Referring to Figs. 5 and 6, it will be noted that the opening 40 in the cover 3, through which the spindle 31 passes, provides a large clearance about the spindle 31, thereby eliminating any need for accurate alignment of the container 2 and its supporting bracket 5 with respect to shaft 33 and bearing 34 on the member 4. In order to seal the opening 40 about the spindle 31, a packing ring 41 of resilient material such as cork is provided to seal against the spindle. The ring 41 has an outside diameter sufficiently large to ensure the ring 41 overlaying the opening 40 for any adjusted position of the spindle 31.

The packing 41 is housed in a threaded member 42 secured to the cover 3 about the opening 40, this member being sufficiently large to accommodate the packing 41 for any adjusted position of the spindle 31. A cap 43 having an aperture 44 of the same diameter as opening 40 and threaded on the member 42, serves to urge the ring 41 into sealing relation with the cover 3 after

4

the container 2 with the agitator 30 positioned therein has been mounted in the bracket 5.

The means 39 serves to support the spindle 31 and agitator 30 in addition to sealing about the spindle 31. Thus, a collar 46 is secured on spindle 31 at a suitable distance above the agitator 30, as by a set screw 47, a thrust washer 48 of suitable material, such as fiber, being interposed between the collar 46 and cap 43.

The coupling 32 between the spindle 31 and shaft 33 comprises a recess 33-a, Fig. 4 formed in the lower end portion of shaft 33 into which the upper end portion 31-a of the spindle 31 is adapted to fit. The upper end of spindle 31 has a diametral slot for engaging a pin 50 carried by the shaft 33 and extending across the recess 33-a. It will be apparent that appropriate axial movement between the spindle 31 and shaft 33 will serve in a simple manner to connect and disconnect the spindle and the shaft.

Furthermore, when the spindle and the shaft are coupled, the telescopic connection provided by the recess 33-a and the upper end portion 31-a of the spindle 31 serves to maintain the spindle and the shaft in substantial alignment and prevent any tendency of the spindle to wobble on its supporting washer 48.

The manner of placing the container 2 in position on the table 4 is as follows: After the can 2 has been provided with a suitable outlet as described in said patent, the original cover is replaced by the cover 3 carrying the agitator 30. The can 2 is then placed in the bracket 5 from below, by movement in a generally axial direction, spindle 31 being inserted in recess 33-a. At this time, the cam 12 is in position to release the band 6 and cap 43 is loose to allow free lateral movement of the spindle 31 and packing 41. After the container is in place, the cam 12 is operated to clamp the band 6 about the container and cap 43 is tightened to compress the packing 41.

When it is desired to remove the container, the cam 12 is operated to release the band 6, and the container is lowered until free of the bracket 5 after which the cover 3 with agitator 30 may be detached for further use. It will be clear that the particular type of coupling 32, greatly facilitates placement and removal of the container 2.

To facilitate withdrawal of the contents from the can 2, a vent 51 may be provided in the cover 3 (see Fig. 7), having a closure member 52 to prevent deterioration of the can contents. This closure member 52 comprises a tapered plug 53 secured to one end of a lever arm 54 pivotally mounted on the cover 3 and resiliently urged into the vent 51. When it is desired to open the vent, the arm 54 is pulled upwardly as by the handle 55 to lift the plug 53 clear of the vent, and swing about its pivot to allow the plug to rest on the cover 3. When it is desired to close the vent, the arm 54 is manipulated to return the plug to the vent. The lever arm 54 is secured to the cover 3 for pivotal movement by a screw 56 passing through a clearance aperture 57 in the arm, whereby the arm may be manipulated also to lift the plug 53 from the vent or to cause it to close the vent. A compression spring 58 confined between the lever 54 and the head of the screw 56 serves to urge the plug 53 into the vent 51.

The inventor claims:

1. In a supporting frame, a resilient band adapted to embrace a container but normally free thereof to permit ready removal or replace-

ment of the container within the band, means to clamp the band about the container, arms for supporting the band and secured thereto at spaced points around the perimeter of the band, said arms extending lengthwise of the axis of the band, a member to which said arms are attached, means securing an arm rigidly to said member, and means securing the other arms to said member, said means providing for limited free transverse movement of the other arms.

2. In a supporting frame, a resilient band adapted to embrace a container but normally free thereof to permit ready removal or replacement of the container within the band, means to clamp the band about the container, arms for supporting the band and secured thereto at spaced points around the perimeter of the band, said arms extending lengthwise of the axis of the band, a member to which said arms are attached, means securing an arm rigidly to said member, and means securing the other arms to said member, said means including a slotted ear projecting from each of said other arms, and means extending through the slot and slidably supporting the ear.

3. In a supporting frame, a resilient band adapted to embrace a container but normally free thereof to permit ready removal or replacement of the container within the band, means to clamp the band about the container, arms for supporting the band and secured thereto at spaced points around the perimeter of the band, said arms extending lengthwise of the axis of the band, a member to which said arms are attached, means securing an arm rigidly to said member, and means securing the other arms to said member, said means including a slotted ear projecting from each of said other arms, and a headed pin extending from said member and through the slot, a separator between the member and the head, said head serving to slidably secure the ear to said member.

4. In apparatus of the character described, a clamping ring adapted to be compressed around a cylindrical object for supporting it, a plurality of arms spaced around the ring and attached thereto, said arms extending lengthwise of the axis of the ring, means providing a fixed support for one of the arms, and means restraining the other arms against substantial movement except in ring expanding and contracting position.

5. In apparatus of the character described, a clamping ring adapted to be compressed around a cylindrical object for supporting it, a plurality of arms spaced around the ring and attached thereto, said arms extending lengthwise of the axis of the ring, means providing a fixed support for one of the arms, and a slot and pin connection between said support and each of the other arms for permitting expansion and contraction of said ring.

6. In a supporting frame, a resilient band adapted to embrace tightly a cylindrical container or to free said container to facilitate placement thereof, within the band or removal therefrom, means including a rotatable cam to clamp the band about the container, a plurality of supporting arms secured to said band in spaced relation around the band, and to a supporting mem-

ber, said arms extending longitudinally of the axis of the band, one of said arms being fixed at its point of attachment to the member to position said band, the other arms at their points of attachment to the member permitting expansion and contraction of such band.

7. In a supporting frame, a resilient band adapted to embrace a container but normally free thereof to permit ready removal or replacement of the container within the band, means to clamp the band around the container, individual arms for supporting the band and individually secured thereto at spaced points around the perimeter of the band, said arms extending upwardly from the band longitudinally of the axis of the band, a member to which said arms are attached, means securing one of said arms rigidly to said member, and means securing the other arms to said member, said last-mentioned means providing for limited free transverse movement of said other arms.

8. In a supporting frame, a resilient band adapted to embrace a container but normally free thereof to permit ready removal or replacement of the container within the band, means to clamp the band around the container, individual arms for supporting the band and secured thereto at spaced points around the perimeter of the band, said arms extending upwardly from the band longitudinally of the axis of the band, a member to which said arms are attached, means securing one of said arms rigidly to said member, and means securing the other of said arms to said member, said last-mentioned means including a slotted ear projecting from each of said other arms transversely of said other arms, and means extending through the slot of each ear and slidably supporting the ear.

9. In a supporting frame, a resilient band adapted to embrace tightly a cylindrical container or to free said container to facilitate placement thereof within the band or removal therefrom, means including a cam rotatable about an axis transversely of the axis of the band to clamp the band about the container, a plurality of supporting arms secured to said band in spaced relation around the band, and also to a supporting member, said arms extending upwardly from the band longitudinally of the axis of the band, one of said arms being fixed at its point of attachment to the member to position said band, the other arms at their points of attachment to the member permitting expansion and contraction of said band.
